U.S. Appl. No. 29/270,502, filed Dec. 22, 2006, Nobili.

* cited by examiner

Primary Examiner—Robert A. Delehanty*Assistant Examiner*—Mark Cavanna(74) *Attorney, Agent, or Firm*—Seed IP Law Group PLLC(57) **CLAIM**

The ornamental design for faucet, as shown and described.

DESCRIPTION

FIG. 1 is a front perspective view of a faucet showing my new design;

FIG. 2 is an enlarged detailed partial perspective view shown broken away thereof; and,

FIG. 3 is a left side elevation view of FIG. 1 with the right side being a mirror image thereof.

The broken line showing of a sink in FIG. 1 is included for the purpose of illustrating environment and forms no part of the claimed design. The broken lines shown in the lower portion of the faucet as seen in FIG. 3 are included for the purpose of illustrating a portion of the faucet that forms no part of the claimed design.

1 Claim, 3 Drawing Sheets*FIG. 1*
